(57) **CLAIM**

The ornamental design for a solar hot water interlocking
rooftile, as shown and described.

DESCRIPTION

FIG. 1 is a top plan view of a solar hot water interlocking
rooftile showing our new design;

FIG. 2 is a bottom plan view thereof;

FIG. 3 is a left end elevational view thereof;

FIG. 4 is a right end elevational view thereof;

FIG. 5 is a front elevational view thereof;

FIG. 6 is a cross sectional view of FIG. 7 shown along line
6—6;

FIG. 7 is a cross sectional view of FIG. 6 shown along line
7—7;

FIG. 8 is a top perspective view thereof;

FIG. 9 is a bottom perspective view thereof; and,

FIG. 10 is a top perspective view of another embodiment of a
solar hot water interlocking rooftop showing our new design.
